(57) **CLAIM**

The ornamental design for a writing instrument, as shown and described.

DESCRIPTION

1. Writing instrument
2. Writing instrument

1.1 : Front

1.2 : Top

1.3 : Left

1.4 : Right

1.5 : Bottom

1.6 : Perspective view from back and left

1.7 : Perspective view from right and front

1.8 : Perspective view with the cap opened

2.1 : Front

2.2 : Top

2.3 : Left

2.4 : Right

2.5 : Bottom

2.6 : Perspective view from back and left

2.7 : Perspective view from right and front

2.8 : Perspective view with the cap opened

Design 1. is a cap-type writing instrument, which is illustrated in Fig. 1.8 with the cap detached; the rear view is omitted because it is a mirror image of the front view;

(Continued)

Design 2. is a cap-type writing instrument, which is illustrated in Fig. 2.8 with the cap detached; the rear view is omitted because it is a mirror image of the front view.

1 Claim, 16 Drawing Sheets
